(57) **CLAIM**

The ornamental design for a clothing article, as shown and described.

DESCRIPTION

FIG. 1 is a perspective view of a clothing article, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken lines showing a person in FIG. 1 are included for the purpose of illustrating the invention in use, and form no part of the claimed design.

The dashed lines featured on the pocket detail of the drawing views represent a stitching line.
